UNITED STATES PATENT OFFICE.

JAMES DOIG, OF BROOKLYN, NEW YORK.

BOX-NAILING MACHINE.

1,335,563.

Specification of Letters Patent. Patented Mar. 30, 1920.

Application filed September 27, 1919. Serial No. 326,897.

To all whom it may concern:

Be it known that I, JAMES DOIG, a citizen of the United States, residing in the borough of Brooklyn, county of Kings, and 5 State of New York, have invented certain new and useful Improvements in Box-Nailing Machines, of which the following is a specification.

My invention relates to box nailing machines, and it has for its object the provision of means in machines of this character for regulating the feed of the fastening devices to the driving means, whereby the 10 number of fastening devices to be driven at each operation of the machine may be predetermined. I will describe a box nailing machine embodying my invention and then point out the novel features thereof in 15 claim.

20 In the accompanying drawings Figure 1 is a view partly in side elevation and partly in vertical section of a box nailing machine embodying my invention. Fig. 2 is a detail view partly in side elevation and partly in 25 vertical section of a portion of the machine shown in Fig. 1 and drawn to a larger scale. Fig. 3 is a top plan view of Fig. 2. Fig. 4 is an enlarged detail view of a device embodying my invention for regulating the 30 feed of the fastening devices to be driven. Fig. 5 is a view similar to Fig. 4 but showing the parts in a different position. Fig. 6 is a detail vertical sectional view taken on the line 6—6 of Fig. 8. Figs. 7 to 10 inclusive are detail views of the feed regulating 35 means, showing it in different combinations.

Similar letters of reference designate corresponding parts in all of the figures.

40 Referring more particularly to Fig. 1, A designates a suitable frame upon which the several parts comprised in machines of this class are arranged. B designates a table for supporting a box C, or other work, into 45 which the fastening devices, such as nails are to be driven. The table B is adjustable in a vertical direction, by means of a screw b in a manner well understood in the art, to provide for different sizes of boxes 50 or different thicknesses of work. D designates a chuck of any well known construction of which there may be any desired number, and suitably supported on the frame A in any well understood manner. The nail or 55 other fastening device is conducted to the chuck through the tube d and is driven into

the box or other work by means of a plunger d¹ comprised in the chuck D. The plungers d¹ of all the chucks D, are engaged by a crosshead E to cause them to simultaneously 60 drive the fastening devices into the work. This is well understood in this art.

F designates a pan or receptacle for receiving the fastening devices. It is mounted to be oscillated in order to arrange the 65 fastening devices or nails in slots (see Fig. 2) from which they feed by gravity into inclined grooves f. The grooves f feed the nails to regulating means, which in turn deliver the nails to a chute f² with which the 70 tubes d are connected.

The regulating means for feeding the nails or other fastening devices to the chucks D comprises pairs of superimposed disks G, G¹. One such pair of disks is provided for 75 each chute f², and they are so arranged as to have their peripheries close to the groove f with which they coöperate.

Each pair of disks G, G¹ are mounted on a gear g, which is suitably journaled in a 80 plate g¹, carried by the frame A. The disks G, G¹ rotate with the gear g and this is accomplished by means of conical studs g² formed on the gear g, which enter openings in the lower face of the disk G¹. A weight 85 g⁴ is provided to hold the disks G, G¹ in engagement with their gear g. The several gears g are driven from a worm g³ suitably mounted in the frame A. The worm g³ is driven from a driving mechanism, it being 90 provided with a gear h⁵.

One of the disks G, G¹ is provided with a series of peripheral notches g⁵, here shown as being in the lower disk g¹, the purpose of which is to receive nails from its groove 95 f and deliver them successively to its associated chuck. When a nail is in one of the notches g⁵, the disk G¹ will carry it from the groove f over the chute f² at which point it leaves the notch and drops into the chute 100 f², which conducts it to the chuck D. This is apparent from Figs. 4 and 5. The other disk, here shown as being the disk G is also provided with a series of peripheral notches g⁶, of different peripheral lengths. The purpose of these notches g⁶ is, that by a relative adjustment between the two disks G, G¹, one, two, three or four of the notches g⁵ can be opened or covered. For example in Figs. 105 4 and 5, only one notch g⁵ is open while the other three are closed. In Fig. 7, two successive notches are open and two successive

- notches g^5 are closed. In Fig. 8, two alternate notches g^5 are open and two alternate notches g^5 are closed. In Fig. 9 three notches g^5 are open, while in Fig. 10 all four notches g^5 are open. With four peripheral notches g^5 , any of the following combinations may be had—four nails fed in succession three nails fed in succession and one blank or miss, two nails fed in succession and two blanks or misses, two nails fed alternately and two alternate blanks or misses, and one nail fed, and three blanks or misses. Obviously the two disks could be adjusted relatively, so that no nails will be fed.
- 15 Any desired means may be employed for holding the two disks in relative adjustment. As here shown, I employ a screw and nut g^8 , which extends through a radial slot g^{10} in the disk G to enter an opening g^9 in the disk G^1 . The nut bears upon the edges of the radial slot so that after the relative adjustment of the disks G , G^1 , they are held in their adjusted positions.
- It will be observed that the wall g^{20} of each peripheral notch g^6 is beveled as is the succeeding marginal surface of the disk G . The purpose of this is, in the event of a nail head dropping onto the disk G^1 in one of the peripheral notches g^6 while still in its groove f , the bevel g^{20} will again raise the nail in its groove f onto the disk G until a notch g^5 registers with the groove f at which time the nail will be conducted from its groove f to its associated chuck D . This operation is illustrated in Fig. 6.
- It will be observed that by my invention any combination of nails may be obtained in a nailing operation. For example the sets of disks G , G^1 may be adjusted so that upon 40 one operation of the machine a certain num-

ber of nails will be driven, and upon the next operation of the machine, either the same or a greater or less number can be driven.

The driving mechanism for operating the 45 various movable parts of machines of this type is well understood in the art. Briefly it comprises a drive shaft K , from which through a train of gears and levers the pan F , is continuously oscillated. An idler shaft 50 k is also driven from the drive shaft K , and upon the operation of a treadle (not shown) a clutch is operated to connect the idler shaft k with a shaft (not shown) carrying a crank k^1 , which is connected with the 55 cross-head E , and a gear k^2 , which drives a shaft k^3 , the upper end of which is provided with the gear k^4 , which meshes with a gear k^5 carried by the worm shaft g^3 .

Having thus described my invention, what 60 I claim as new is:

In a box nailing machine in combination, means for driving the fastening devices; means for feeding the fastening devices to the driving means; means for regulating 65 the feed of the fastening devices comprising a pair of superimposed disks, one of which is provided with peripheral notches which receive the fastening devices and the other of which is also provided with notches 70 but of different peripheral lengths, and said disks being relatively adjustable whereby one or more of the receiving notches may be covered; and a bevel on one of the marginal walls of each of the elongated peripheral notches.

JAMES DOIG.
